GASEOUS ELECTRIC DISCHARGE LAMP
DEVICE

Marcello Pirani, Berlin-Wilmersdorf, and Martin
Reger, Berlin, Germany, assignors to General
Electric Company, a corporation of New York

Application July 21, 1933, Serial No. 681,592
In Germany August 19, 1932

5 Claims. (Cl. 176—122)

5 The present invention relates to gaseous electric discharge lamp devices generally and more particularly the invention relates to improvements in concentrated light sources useful in connection with television, sound reproduction, spec-
trometry and similar arts.

10 The object of the present invention is to provide a gaseous electric discharge lamp device which is a concentrated, brilliant, uniform, high intensity point light source. Another object of the invention is to provide such a lamp device startable and operable on either alternating or direct current. A further object of the invention is to provide a lamp device of the above type 15 wherein high current densities can be used. A further object of the invention is to provide a gaseous electric discharge lamp device of the above type wherein the vapor of difficultly vaporizable metals, such as sodium, constitutes the gaseous filling or is a component of the gaseous filling. A still further object of the invention is to provide such a lamp device of simple structure and the manufacturing cost of which is reduced to a minimum. Further objects and advantages 20 25 attaching to the device and its use and operation will be apparent to those skilled in the art from the following particular description.

The invention attains its objects by providing a metal housing in the glass container of a gaseous electric discharge lamp device completely enclosing the gaseous electric discharge. The interior of said housing is divided by a wall having a communicating passage therein. A thermionic electrode is mounted on each side of said wall 30 in said housing out of line with the passage in said wall. The light emitted by the gaseous electric discharge passes through an opening in said housing co-axial with the communicating passage in said wall, and the gaseous electric discharge in the device is viewed end on through said opening. A concentrated, high intensity light spot of great surface brightness and uniformity is thus made available for use in the arts generally. When the wall dividing the metal housing 40 45 is of metal it will be understood, of course, that the potential applied to the device is greater than the sum of the cathode and anode potential drop of any gaseous electric discharge which might take place between the electrodes and the walls of the housing. The gaseous electric discharge then follows a path through the communicating passage in the partition. A lamp device having the above structure is easily and inexpensively 50 55 manufactured and high current densities can be

used in the device. Since high current densities can be used in this type of gaseous electric discharge lamp device it is possible to vaporize in the lamp metals having a vaporization temperature of over 500° C., such as alkali earth metals which vaporize at a temperature of between 600°—800° C. as well as metals having a lower vaporizing temperature, such as mercury. The vaporized metal is then present in the gaseous electric discharge path and the spectrum of the light emitted by the lamp is strong in the rays characteristic of the metal vapor. When such metal vapors are used in the lamp we prefer to use a starting gas, such as argon, at a pressure appreciably greater than that of the metal vapor pressure in order to reduce the rate of diffusion of the metal vapor through the opening in the housing to a minimum. Baffles are also used for this purpose, when desired. The metal housing attains at the highest a dull red temperature and does not emit light of an intensity which would mix with the light emitted by the gaseous electric discharge in the device. The housing is separated from the walls of the glass container of the device so that said glass walls of the container do not attain a dangerous temperature during the operation of the device.

In the drawing accompanying and forming part of this specification two embodiments of the invention are shown in which

30 Fig. 1 is a side elevational view of one embodiment of the invention,

Fig. 2 is a similar view of the same embodiment turned 90° from the position shown in Fig. 1, and

Fig. 3 is a side elevational view of another embodiment of the invention.

35 Like numbers denote like parts in all the figures.

Referring to Figs. 1 and 2 of the drawing the new and novel lamp device comprises a bulb like glass container 1 having a stem 2. Current leads 4 and 5 are sealed into the pinch part 3 of said stem 2 and electrodes 10 and 11 are mounted on the ends of said leads 4 and 5. Said leads 4 and 5 are enclosed in tubes 17 and 18, respectively, of insulating material, such as magnesium oxide, 40 to prevent an electric discharge between said leads 4 and 5 and to insulate said leads 4 and 5 from the walls of a metal housing 6 mounted in said container 1. Said housing 6 is of rectangular shape and is made of sheet metal. Supports 7 and 8 fused into the pinch part 3 of said stem 2 are provided for said housing 6. The space in said housing 6 is divided into two parts by a diagonal wall 9 of sheet metal 45 and one of said electrodes 10 and 11 is located 50 55

in each of said parts. Said electrodes 10 and 11 are electron emitting when heated and comprise a metal filament, such as a tungsten filament, coated with an electron emitting material, such 5 as barium oxide. A cylindrical tube 12 of small internal diameter pierces said partition 9 to form a communicating passage between the two parts of said housing 6. The top wall of said housing 6 has an opening therein co-axial with said tube 10 12 and which is indicated at 13. Said thermionic electrodes 10 and 11, which operate at an incandescent temperature, are out of line with said tube 12 and are not visible through the opening indicated at 13. The discharge path between 15 said electrodes 10 and 11 goes through said tube 12 when the potential applied across the electrodes 10 and 11 is greater than the combined anode and cathode potential drop of a discharge between said electrodes 10 and 11 and the walls 20 of said housing 6 and the gaseous electric discharge is concentrated in said tube 12. The part 25 of the gaseous electric discharge located in said tube 12 is visible end-on through the opening 13 and is a concentrated, brilliant, uniform, high intensity spot, or point source of light. The gaseous electric discharge is completely surrounded by the housing 6.

Said container 1 is filled with a rare gas, such 30 as argon or neon, at a pressure of approximately 1-10 mm. When desired, a vaporizable material, such as mercury or sodium, is located in said housing 6 and said container 1 is filled with a starting gas, such as argon or neon. When a mixture of a metal vapor and a gas is used we 35 prefer to have the pressure of the starting gas appreciably greater than the maximum metal vapor pressure to reduce the rate of diffusion of the metal vapor from housing 6 to container 1 through the opening 13 to a minimum. This is 40 particularly important where an alkali metal vapor, such as sodium vapor, is used as a component of the gaseous filling to protect the glass container from the chemical effects of such vapor. Said container 1 is made of a glass resistant to 45 the chemical effects of the alkali metal vapor, when desired. The gaseous electric discharge between said electrodes 10 and 11 first takes place in the rare gas. The gaseous electric discharge raises the temperature of said housing 6 and the 50 vaporizable metal contained in said housing 6 to the vaporization temperature of the metal and the metal is then present in vaporous form in the discharge path during the operation of the device. The spectrum of the light emitted by the device is 55 rich in rays characteristic of the metal vapor during the operation of the lamp device. The housing 6 is separated an appreciable distance from the walls of container 1 which protects said walls from the heat of the gaseous electric discharge during the operation of the lamp. High current 60 densities necessary to generate enough heat to vaporize the alkali metal can therefore be used in the lamp without injury to the glass walls of the container 1. The use of high current densities is made possible by electron emitting electrodes 10 and 11.

The embodiment of the invention illustrated in Fig. 3 is similar in all respects to that illustrated in Figs. 1 and 2 except that in this embodiment the partition 9 is vertical and the electrodes 10 and 11 are in the same horizontal plane. The tube 12 is located above said electrodes 10 and 11 and the longitudinal axis thereof is parallel to the plane of said electrodes. The ends of 75 said tube 12 extend beyond said electrodes 10 and

11. A tube 14, which is co-axial with said tube 12, protrudes from one of the side walls of said housing 6 and acts as a baffle for the particles of vaporized material in said housing to retard the rate of diffusion of the metal vapor from the housing 6 to container 1. The glass walls of said container 1 are thus kept free from undesired light absorbing deposits of condensed material and said walls are protected from the chemical effects of the vapor filling. The gaseous electric discharge is visible through the opening in said tube 14 and is a concentrated, bright, intense, uniform spot of light. A ring-shaped electrode 15 mounted on current lead 16 sealed into the pinch part 3 of said stem is adjacent the external 15 end of said tube 14 and is concentric with the longitudinal axis of said tube 14. Said electrode 5 is connected as an auxiliary starting electrode when the electric discharge device is operated on alternating current and as an anode when the device is operated on direct current, when desired.

While we have shown and described and have pointed out in the annexed claims certain novel features of the invention, it will be understood that various omissions, substitutions and changes 25 in the forms and details of the device illustrated and in its use and operation may be made by those skilled in the art without departing from the broad spirit and scope of the invention, for example, any of the well known types of thermionic electrode, such as the oxide coated, metal shell-type Hull electrode, or the mixed, sintered metal and oxide type Pirani electrode, can be used in place of the electrodes 10 and 11, shown and described.

What we claim as new and desire to secure by Letters Patent of the United States is:—

1. An electric discharge device comprising a container, electrodes sealed therein, a gaseous atmosphere therein, a housing in said container, a vaporizable material in said housing, said housing being divided into chambers by a partition having a communicating passage of appreciable length therein, one of said electrodes being mounted in each of said chambers, and one of the 45 walls of said housing being perforated in line with said communicating passage, the end of said passage being at an appreciable distance from the opening in said housing.

2. An electric discharge device comprising a 50 container, electrodes sealed therein, a gaseous atmosphere therein, a housing in said container, a vaporizable material in said housing, said housing being divided into chambers by a partition having a communicating passage of appreciable 55 length therein, one of said electrodes being mounted in each of said chambers, out of line with said passage and one of the walls of said housing being perforated in line with said communicating passage, the end of said passage being at appreciable distance from the opening in said housing.

3. An electric discharge device comprising a 65 container, electrodes sealed therein, a gaseous atmosphere therein, a housing in said container, a vaporizable material in said housing, said housing being divided into chambers by a partition having a communicating passage of appreciable 70 length therein, one of said electrodes being mounted in each of said chambers, a tube in the wall of said housing co-axial with said communicating passage and spaced an appreciable distance from the end of said passage.

4. An electric discharge device comprising a 75

5 container, electrodes sealed therein, a gaseous atmosphere therein, a housing in said container, a vaporizable material in said housing, said housing being divided into chambers by a partition having a communicating passage of appreciable length therein, one of said electrodes being mounted in each of said chambers, a tube in the wall of said housing co-axial with said communicating passage and spaced an appreciable distance from the end of said passage, another of said electrodes being mounted outside of said housing and adjacent the external end of said tube.

5. An electric discharge device comprising a container, electrodes sealed therein, a gaseous atmosphere therein, a housing in said container, said housing being divided into chambers by a partition having a communicating passage of appreciable length therein, one of said electrodes being mounted in each of said chambers, and one of the walls of said housing being perforated in line with said communicating passage, the end of said passage being at an appreciable distance 10 from the opening in said housing.
